United States Patent Office.

JOSEPH B. PEDRICK, OF LOWELL MILLS, INDIANA, ASSIGNOR TO HIMSELF
AND JOSEPH F. GENT, OF SAME PLACE.

Letters Patent No. 82,027, dated September 8, 1868.

IMPROVEMENT IN RECIPROCATING STEAM-ENGINES.

The Schedule referred to in these Letters Patent and making part of the same.

TO ALL WHOM IT MAY CONCERN:

Be it known that I, JOSEPH B. PEDRICK, of Lowell Mills, in the county of Bartholomew, in the State of Indiana, have invented a new and improved Device for Controlling and Reversing Steam-Engines; and I do hereby declare that the following is a full and exact description thereof, reference being had to the accompanying drawings, and to the letters of reference marked thereon.

The nature of my invention consists in providing a valve-box, or combination of boxes, as shown in Figure 1, perspective, and marked G and M.

M is a valve-box containing a valve, K, the use of which is to make the pipes B A and D C feed and exhaust-pipes alternately to and from the cylinders, for a better understanding of which reference is had to the vertical sectional view, Figure 2, in which H is the pipe connecting with the boiler, and I is the escape-pipe.

Figure 3 is a valve. The bottom, or portion that rests upon the seat, is shown, and marked Y.

This is the same valve shown in the valve-box M, and marked K, fig. 2, and is double, that is, it has two openings through it, one of which connects with the pipes B and A, and the other with the pipes D and C.

This valve is worked by the lever O, and when the lever is thrown forward or towards the valve-box M, the steam will pass through the valve K, and into the pipe D, fig. 2; thence into the valve-box E N, and above the plate P; thence through the plate and valve into the cylinder, from which it exhausts into the box E N; thence to the pipe B, thence to the box M, thence through the pipe I.

When the lever O is thrown backward, or from the valve-box, the steam will pass into the pipe B; thence into the box E N; thence into the cylinder, from which it will exhaust through the valve L; thence through the pipe D into the box M; thence through the pipe I.

If the lever is brought to a perpendicular, the valve K will shut the steam all off from the cylinders.

The farther the lever O is moved from a perpendicular, the more steam it will admit, and the nearer it approaches a perpendicular, the less it will admit to the engine, thereby giving complete control over the same.

When it is desired to run both engines in the same direction at the same time, and in opposite directions at other times, the double valve K should be made in two parts, as shown in Figure 4, each part to be worked by a lever in the usual manner.

The valves are all so constructed as to admit of packing between them and their respective plates.

What I claim, and desire to secure by Letters Patent, is—

The arrangement of the valve K, valve-boxes G M, and the pipes B A and C D, substantially as shown and described.

JOSEPH B. PEDRICK.
